UNITED STATES PATENT OFFICE.

ALLEN M. MARK AND BLAKE H. McELVAIN, OF DENVER, COLORADO.

CENTRIFUGAL SEPARATOR.

1,283,846.

Specification of Letters Patent.

Patented Nov. 5, 1918.

Application filed February 18, 1916. Serial No. 79,023.

To all whom it may concern:

Be it known that we, ALLEN M. MARK and BLAKE H. McELVAIN, citizens of the United States, residing at the city and county of Denver and State of Colorado, have invented certain new and useful Improvements in Centrifugal Separators; and we do declare the following to be a full, clear, and exact description of the invention, such as will enable others skilled in the art to which it appertains to make and use the same, reference being had to the accompanying drawings, aid to the characters of reference marked thereon, which form a part of this specification.

Our invention relates to improvements in centrifugal separators and is adapted for the separation of all commingled materials varying in specific gravity. The principal use for the machine which we have in mind is the separation of precious and other metals or mineral substances from the gangue or rock with which they are found mingled either in the natural state as placer material, 25 or in the shape of pulverized rock or quartz.

Our object is to provide a machine of this class which shall be adapted to efficiently perform the aforesaid function and which shall at the same time be comparatively simple in construction and economical in cost.

The construction comprises in its simplest form a pan mounted to rotate and having walls inclined outwardly as they extend upwardly from the bottom, said walls being equipped with a series of riffles which may be either separate and distinct from each other or in spiral form as may be desired. Where the riffles are arranged in parallel relation or forming distinct convolutions, the metallic values in whatever form, will be caught below the riffles and held by the action of centrifugal force in direct contact with their lower surfaces and the adjacent wall of the pan, while the gangue or material of less specific gravity will travel upwardly over the riffles and be discharged at the top of the pan whence it may pass directly into a waste launder, or where a plurality of pans is used, the material which passes over the top of the innermost pan, will come in contact with a depending stationary wall whereby it will be guided downwardly into the bottom of the rotary pan, where it will be again acted on by the centrifugal force and brought into contact with another set of

riffles arranged on an inclined wall outwardly positioned from the first named wall. In this way the material which is discharged at the top of the first member of the pan, may be subjected to the action of any desired number of other and similar riffled members arranged successively outwardly from the first member, but all preferably mounted on the same bottom and caused to rotate in unison.

Where the riffles are in spiral form, it is intended that the metallic values which are caught thereby will travel gradually upwardly under the influence of centrifugal force, taking a spiral path according to the pitch of the riffle members, the metal values being finally discharged through an opening in the pan adjacent the upper extremity of the spirally arranged riffle. In this case the discharge of the values is continuous and automatic while in the case where the riffles are distinct and separate the values which are caught remain in their deposited position until it shall be desired to clean up, in which event they may be removed in any desired manner.

Having briefly outlined our improved construction we will proceed to describe the same in detail, reference being made to the accompanying drawing, in which is illustrated an embodiment thereof. In this drawing,—

Figure 1 is a vertical section taken centrally through our improved centrifugal separator, the section being taken on the line 1—1, Fig. 2.

Fig. 2 is a fragmentary top plan view of the machine, or a view looking in the direction of arrow 2, Fig. 1.

Fig. 3 is an elevation of the machine showing the launder composed of two hinged members which are opened or swung outwardly from each other, to expose the exterior pan of the structure.

Fig. 4 is a fragmentary sectional view of the pan shown on a larger scale.

Fig. 5 is a detail view showing the wall of the pan and a riffle on a larger scale.

Fig. 6 is a fragmentary view illustrating the manner of hinging the gangue launder, 105 being a view looking in the direction of arrow 6, Fig. 2.

Fig. 7 is a detail view showing a section of the stationary wall which separates two riffled wall members of the rotary pan.

Fig. 8 is a view similar to Fig. 1 but illustrating a pan equipped with a spirally arranged riffle.

Fig. 9 is a section taken on the line 9—9, 5 Fig. 8, shown on a larger scale.

The same reference characters indicate the same parts in all the views.

Referring first more particularly to Figs. 1 to 7 inclusive, let the numeral 5 designate 10 a pan composed of a bottom 6 having one or more inclined walls, two being shown in the drawing and respectively designated 7 and 8. The bottom 6 of this pan is secured to a disk 9 by means of suitable fastening 15 devices 10, the said disk being formed integral with the upper extremity of a shaft 12 whose lower extremity is journaled in a step box 13 and whose upper extremity is provided with a flange 14 having a circular 20 groove to receive ball members which engage a coöperating groove formed in a stationary member 15. Rotary movement is imparted to the shaft 12 in any suitable manner. As shown, a horizontally disposed 25 shaft 16 is journaled in bearings 17 and 18, said shaft being provided with an operating pulley 19 at its outer extremity and a bevelled gear 29 at its inner extremity, the said gear meshing with a horizontally disposed 30 coöperating gear 20 made fast to the shaft 12 by a set bolt 21. Each of the walls 7 and 8 of the pan are flared outwardly as they extend upwardly, and while this inclination 35 may be regulated as may be desired or as circumstances or conditions or the material to be treated may dictate or suggest, the preferred inclination so far as our experiments have gone is 45 degrees approximately. The wall members 7 and 8 are rigidly secured 40 to the bottom of the pan and rotate therewith. Each of these wall members is provided with a series of spaced riffles 22 which, as shown in the drawing, are circular in cross section and decrease in diameter 45 from the bottom upwardly though it must be understood that the invention is not limited to this particular cross sectional area of the riffles nor to their relative size, since, if desired they may be made all of the same 50 cross sectional area or they may vary in size with a different relative arrangement if for any reason it may be desired so to do. The riffles may be secured to the wall members of the pan in any suitable manner. As 55 shown in the drawing (see Fig. 5) solder 23 is employed to perform this function.

The two wall members 7 and 8 are spaced by a stationary partition 24 which is secured to the top 25 of the launder 26 by means of 60 angle brackets 27, bolts 28 and coöperating wing nuts 30. It is evident that any suitable means may be employed for supporting this partition 24 in coöperative stationary relation with the two rotary, riffled pan 65 members. The upper extremity 31 of this

partition is preferably vertically disposed and extends above the upper edges of both pans. This part 31 forms a sort of baffle which prevents the material which escapes under the action of centrifugal force, at the 70 top of the pan member 7, from passing into the waste launder 26 until after it has been treated by the pan member 7 and the partition 24. The partition 24 is interrupted at the bottom, to allow the material after passing downwardly through the space 32, to come in contact with the bottom or rotary part of the pan, and as soon as this occurs, the material immediately begins to travel upwardly into contact with the riffles 22 of 80 the pan member 8. The material which escapes at the upper edge of the last named pan member, passes into the waste launder 26 and finally escapes through a spout 33. It is evident that any desired number of 85 these pan members may be employed, and by virtue of this construction the material which has escaped from one pan member, if it still retains values, may be subjected to the treatment of another pan member and 90 so on until it has been impoverished of all of its metallic content.

As shown in the drawing, the launder 26 is composed of two members hinged as 95 shown at 34 to stationary uprights 35, the two members being respectively designated by the numerals 36 and 37. When the machine is in use, the launder members are connected by means of clips 38 mounted on one extremity of the member 36, which engage catches 39 mounted on the adjacent extremity of the other launder member. This launder member is composed of a top wall, a vertically disposed outer wall 40 and an upwardly projecting inner wall 41 which is 105 spaced from the outer wall and varies in height. This launder in addition to being supported by its hinges, is also supported by arms 42 and 43 which are secured to the stationary frame and extend upwardly into engagement with the bottom of the launder. When it is desired to open the launder to the 110 position shown in Fig. 3, it is evident that the clips 38 must not only be disconnected from the catches 39, but the top of the launder must be disconnected from the angle brackets 27 and also from a centrally located distributing member 44 which is equipped with arms 45 which are secured to the top 115 of the launder by bolts 46 and wing nuts 47. This distributing member 44 is suspended 120 from the top of the launder and is approximately cone-shaped, its smaller extremity being uppermost and located directly below the feed or funnel 48. A feed conduit 49 passes through the inlet 48, its lower extremity being positioned slightly above the upper extremity of the distributing member. The base of this distributing member is raised 125 slightly above the bottom of the pan since 130

the distributing member is stationary when the machine is in operation, and it is, therefore, not desirable that it should be in actual contact with the pan. The distributing member performs an important function, since it is not desirable that the material to be treated should be fed directly into contact with the center of the bottom of the pan, since there is no motion at the center, and so little motion of the area close to the center that the centrifugal force would not act advantageously and quickly upon the material to be treated.

In the form of construction shown in Figs. 1 to 3 inclusive, the material to be treated is first fed through the conduit 49 into contact with the distributor which discharges it upon the bottom of the pan at some distance from its mathematical center. The pan is put in motion at the desired speed, through the instrumentality of suitable mechanism as that illustrated in the drawing. As soon as the material strikes the bottom of the pan or leaves the distributor, it immediately commences to travel outwardly under the action of centrifugal force and the metallic values which are heaviest, are brought into direct contact with the lower surface of the riffles adjacent the wall 7 of the pan and are held in such close contact therewith as to prevent their escape. The mineral values of varying specific gravities are caught and classified by the riffles while the lighter material is carried upwardly and first discharged at the upper extremity of the wall 7. If more than one wall is employed this material will then slide downwardly in contact with the stationary partition 24, and come into contact with the outer portion of the bottom of the pan, where it will be again acted on by centrifugal force and brought into contact with the riffles of the pan member 8, where the operation heretofore described will be repeated. It is assumed that the material which finally escapes at the upper edge of the pan member 8, will be impoverished of its metallic values. It then enters the launder 26 and is discharged from the machine through the spout 33.

In the form of construction shown in Fig. 8, the wall member 7 of the bottom 6 of the pan is equipped with a spirally arranged riffle 50 which commences near the bottom of the pan and terminates near the upper extremity thereof. The upper portion of the wall of the pan is provided with an opening 51 covered by a housing 52, the extremity 53 of the housing being closed just beyond what may be termed the forward extremity of the opening 51, since when the mineral values which have followed the spirally arranged riffle reach the discharge opening 51, they will be traveling in the direction indi-

cated by the arrow *a* in Fig. 8. The metallic values which pass through the opening 51, enter a launder 54 and are discharged from the machine through a spout 55. In this case the gangue passes upwardly over the riffles and over the upper edge of the pan into a launder compartment 56 and finally escapes through a spout 57.

In other respects the form of construction shown in Fig. 8 is substantially the same as shown in the other views. It is also evident that there may be a number of riffled wall members in this form of construction the same as in the other form, though only a single such member is shown in Fig. 8 of the drawing.

As illustrated in Fig. 3, each wall member of any pan may be composed of a number of distinct sections, which are retained in place by overlapping clips 58. These sections are locked in place by a hoop or metal band 59 which is exteriorly secured to the upper part of the pan and clamped in place by means of a bolt 60 passing through opposing lugs with which the adjacent extremities of the hoop are equipped. The pan sections should be provided with a number of stop lugs 61 to prevent the hoop from sliding downwardly on the pan. The sectional form of the pan is believed preferable for convenience of transportation. As shown in the drawing, the partition 24 may also be composed of sections, a single section of this partition being illustrated in Fig. 7.

Having thus described our invention, what we claim is,—

1. A centrifugal separator comprising a pan having its walls flared outwardly from the bottom of the pan, means for feeding material to the pan, a spiral riffle extending around the inner face of said flared walls, an opening through the wall of the pan immediately below and adjacent the end of the uppermost portion of the riffle, a covering over said opening open at one end and closed at the other to prevent concentrates from passing beyond the opening, a launder to receive discharge from said opening, and a launder to receive discharge from the upper edge of the pan.

2. A centrifugal separator comprising a pan mounted to rotate and having a wall flared outwardly from its bottom, a launder arranged exteriorly of the said pan, a stationary distributing device suspended from said launder and occupying a central position within the pan, and means for feeding the material to be treated into contact with the said device.

3. A centrifugal separator comprising a pan mounted to rotate, means for actuating the pan, the wall of the pan being downwardly inclined from its outer edge to the bottom and equipped with riffles arranged to

intersect the lines of centrifugal force, a launder arranged exteriorly of the said pan, a stationary cone shaped distributing device suspended from said launder and occupying 5 a central position within the pan, and means for feeding the material to be treated into contact with the upper extremity of said device.

In testimony whereof we affix our signatures in presence of two witnesses.

ALLEN M. MARK,
BLAKE H. McELVAIN.
